UNITED STATES PATENT OFFICE

128,271

DESIGN FOR A CLOCK

George W. Walker, Pleasant Ridge, Mich., assignor to The Standard Products Company, Detroit, Mich., a corporation of Ohio

Application May 21, 1941, Serial No. 101,055

Term of patent 7 years

To all whom it may concern:

Be it known that I, George W. Walker, a citizen of the United States and a resident of Pleasant Ridge, in the county of Oakland and State of Michigan, have invented a new, original, and ornamental Design for a Clock, of which the following is a specification, reference being had to the accompanying drawing, forming a part thereof.

In the drawing, Fig. 1 is a perspective view of a clock, showing my new design; Fig. 2 is an end elevational view thereof; Fig. 3 is a front eleva-

tional view thereof; Fig. 4 is a rear elevational view thereof; and Fig. 5 is a top plan view thereof.

The characteristic features of my design reside in the portions shown in solid lines, the clock face, for example, being of conventional form.

I claim:

The ornamental design for a clock, substantially as shown and described.

GEORGE W. WALKER.
